UNITED STATES PATENT OFFICE.

ANTOINE W. MARTIAL, OF HOUSTON, TEXAS.

COT.

SPECIFICATION forming part of Letters Patent No. 270,961, dated January 23, 1883.

Application filed November 28, 1882. (No model.)

To all whom it may concern:

Be it known that I, ANTOINE W. MARTIAL, a citizen of the United States, residing at Houston, in the county of Harris and State of Texas, 5 have invented a new and useful Cot, of which the following is a specification, reference being had to the accompanying drawings.

This invention relates to cots; and it has for its object to provide a simple, durable, inexpensive, and efficient device, consisting of separable pieces that can be readily and conveniently disconnected and arranged in compact form for transportation from place to place.

In the drawings, Figure 1 is a perspective view of my improved cot in position ready for use. Fig. 2 is a longitudinal sectional view on the line x , Fig. 1. Fig. 3 is a transverse sectional view taken through one of the end supports. Fig. 4 is a perspective view of the parts 20 composing my improved cot packed in position for transportation.

Referring to the drawings, A designates the frame of my cot, and B the flexible bed-bottom. The former consists of a number of separable 25 and independent pieces comprising two longitudinal top rails, C C, which are supported by X-shaped end portions, D D. The top rails, C C, each consist of two end rods, c c, having a lateral cylindrical socket, a', and connected by 30 one or more intermediate rods, a'', all of these rods being joined by cylindrical sockets a'', as shown. The X-shaped end supports, D D, each consists of an X-shaped cylindrical socket, d', and four connecting-rods, d'', which fit in the 35 arms of the socket d'. The two bottom rods d'' rest on the ground or floor, while the two top rods d' have their ends fitted in the sockets a''. The ends of the different rods which enter the cylindrical sockets are preferably 40 provided with metallic ferrules E, as shown.

The flexible bottom B is provided with a series of eyes or eyelets, b', at its side edges, which eyes are hooked over a corresponding series of hooks, a'', on the rails C C when the 45 frame is put together.

The advantages of my invention will be readily understood and appreciated. When it is desired to pack the cot for transportation the flexible bottom is first removed from the frame, after which the latter is taken apart and 50 the pieces thereof placed compactly together in a bundle with the flexible bottom. In this cot there are no pivot-joints to become worn or get out of order, and should any of the separable pieces become broken or damaged they 55 can be readily replaced.

If desired, the ferrules E may be screw-threaded to enter screw-threads on the interior of the sockets, as shown at S, Fig. 2.

I claim as my invention—

1. A cot consisting of separable and independent pieces having no hinge or pivot joints, and comprising a frame and removable flexible bed-bottom, as set forth. 60

2. The combination, in a cot, with a separable frame, of a flexible bed-bottom independent and removable in connection with the frame, and suitable means for fastening the bottom to the frame, as set forth. 65

3. The herein-described cot-frame, comprising longitudinal top rails formed of separable pieces, the end ones of which are provided with lateral sockets, and substantially X-shaped supports formed of a central radial socket-piece and separable rods to be fitted therein, 70 as set forth.

4. In a cot, the combination of longitudinal top rails having lateral sockets at their ends, end supports comprising central radial socket-pieces and rods to be fitted therein, and a flexible bed-bottom having a series of eyes at its edges to engage a corresponding series of hooks on the top rails, as set forth. 75

In testimony that I claim the foregoing as my own I have hereto affixed my signature in presence of two witnesses. 80

ANTOINE WILLIAM MARTIAL.
